CAR PULLER

William E. Goodman, Chicago, Ill., assignor to
Goodman Manufacturing Company, Chicago,
Ill., a corporation of Illinois

Application May 8, 1933, Serial No. 669,928
Renewed July 14, 1934

25 Claims. (CL 214—41)

This invention relates to improvements in car ring carried by jacks 15, 15 interposed between the pullers and has among other objects to provide a new and improved device of the class described of a novel, simplified, efficient, and compact construction, operated and controlled in a novel and simplified manner, which device is particularly adapted for use with and to be driven by a conveyor of the shaker or jiggling type.

Other objects of my invention will appear from time to time as the following specification proceeds.

My invention may be more clearly understood with reference to the accompanying drawings wherein:

Figure 1 is a partial diagrammatic plan view of the device of my invention in operation in a mine;

Figure 2 is an enlarged side elevation of the device shown in Figure 1 with parts broken away;

Figure 3 is an enlarged side elevation of the device of my invention with certain parts broken away and in section to more clearly show the details thereof;

Figure 4 is an enlarged plan view of the device shown in Figure 3 with parts broken away and in section to show certain other details of the device embodying my invention than are shown in Figure 3; and

Figure 5 is a sectional view taken substantially along line 5—5 of Figure 3.

Like numerals refer to like parts throughout the several figures.

Referring now in particular to the drawings illustrating one embodiment of my invention, a shaker conveyor pan line 10 is provided. The pan line 10 is reciprocably driven from suitable conveyor drive mechanism in an ordinary manner so that material, such as coal, may readily be moved there along in a direction away from the working place and be discharged into mine cars or other material receiving means. As herein shown, the shaker conveyor pan line 10 is so arranged as to discharge material into suitable mine cars 11 on a track 12, and suitable means of a new and novel construction are provided for moving said cars along said track at a controlled rate of speed beneath the discharge end of said pan line during the loading operation for controlling the loading of said cars which includes a car puller, generally indicated by reference character 13.

With reference now in particular to the details of the car puller 13 and certain of the novel features of my invention, a support frame 14 is provided. The support frame 14 may rest on the mine floor but is herein preferably shown as be-

ing supported by the mine roof and mine bottom and is arranged so that its longest dimensions extend transversely of the pan line 10. The support frame 14 is adapted to be held on the jacks 15, 15 in various positions of vertical adjustment with respect thereto by means of split collars 16, 16 secured to said support frame and clamped to the jacks 15, 15 by means of suitable nuts and bolts 17, 17 in a usual manner. A shaft 18 is carried by the support frame 14 and extends longitudinally of the pan line 10 and has a winding drum 19 carried thereon for free rotation with respect thereto.

The winding drum 19 is provided with a ratchet 20 adjacent one side thereof and a ratchet 21 adjacent the opposite side thereof. The ratchet 20, when engaged by a pawl 22 on a rocking member 23 carried by the shaft 18 for rocking movement with respect thereto, acts as a means for imparting rotational movement to the winding drum 19 upon rocking movement of said rocking member, while the ratchet 21, engaged by a dog 24, pivotally mounted on an upstanding bracket 25, acts as a means for restraining rotation of said winding drum in an opposite direction to which it is being driven by the pawl 22.

An arm 27 extends angularly downwardly from the rocking member 23 and has a tension spring 28 connected to its free end, the opposite end of which tension spring is connected to the jack 15 adjacent the winding drum 19 for holding the rocking member 23 in a generally upright position and forming a means against which said rocking member may react during rocking movement thereof. Another arm 29 extends longitudinally from the rocking member 23 in a generally horizontal plane and has a bifurcated outer end 30 which carries a winding drum 31. The winding drum 31 is carried on a shaft 32 having squared ends adapted to be engaged by a suitable crank or wrench (not shown) and is held from rotation in a direction opposite to which it is adapted to be rotated by means of a spring pressed dog 33 adapted to engage suitable ratchet teeth 34 formed integral with said drum.

A flexible member 35, such as a wire rope or cable, is secured to the winding drum 31 and is adapted to be wound thereon. As herein preferably shown, the flexible member 35 extends upwardly from the winding drum 31 and over a guide sheave 36 supported in a bracket 37 extending upwardly from the support frame 14. From the guide sheave 36, the flexible member 35 extends outwardly in alignment with the longitudinal center line of the pan line 10 and is se-

cured to the outer end thereof in a suitable manner so as to exert a pull on the winding drum 31 against the ratchet teeth 34 and dog 33 and move the arm 29 in an upwardly direction upon movement of said pan line in one direction and permit said arm to return to its initial starting position upon movement of said pan line in an opposite direction.

It may thus be seen that upon reciprocation of the pan line 10, the flexible cable 35 will cause 10 rocking movement of the arm 29 which will in turn rock the rocking member 23 about the axis of the shaft 18 and change the rectilinear movement of the shaker conveyor pan line to rotational movement through the pawl 22 engaged with the ratchet 20 for rotating the winding drum 19. Slack in 15 the flexible cable 35 may be taken up by means of the winding drum 31 and differences in the length of the pan line may be compensated for by means 20 of said winding drum in an obvious manner while tension of the tension spring 28 may be adjusted by winding in said flexible cable on said winding drum.

With reference now to several other of the 25 novel features of my invention and the means for controlling rotation of the winding drum 19 from a point remote from said winding drum and increasing tension on the flexible cable 35 as said winding drum is being operated, a guide cam 39 is carried on a boss 40 of the support frame 14 for pivotal movement with respect thereto about an axis coaxial with the shaft 18. The guide cam 39 is provided with a depending arm 41. The free end of the depending arm 41 has a tension spring 42 connected thereto, the opposite 30 end of which tension spring is connected to a member 43 depending from the arm 29 adjacent the outer end thereof but herein preferably shown as being disposed inwardly of the winding drum 31.

An arm 44 is formed integral with the pawl 22 and extends therefrom and has a roller 45 journaled on its outer end, which roller is adapted to ride on the upper surface of the guide cam 39. Suitable means are provided for controlling 45 pivotal movement of the guide cam 39 about the axis of the shaft 18 which may be of any type but which is herein shown as being a relatively flexible member 46 working against the tension spring 42 so that it may be controlled from a 50 position remote from the winding drum 19.

When the guide cam 39 is positioned so that the roller 45 may ride thereon during the entire stroke of the arm 29 and rocking member 23, the pawl 22 is held in a disengaged position from the ratchet 20 and the winding drum 19 is held from rotation in a direction opposite to which it is adapted to be driven by means of the dog 24 engaging the ratchet 21. As the guide cam 39 is pivotally moved about the axis of the shaft 18, the pawl 22 is permitted to engage the teeth of the ratchet 20. The number of teeth which the ratchet 20 may move the winding drum 19 per stroke of the rocking member 23 is thus controlled by movement of the guide cam 39 so that the pawl 22 may move said winding drum a distance of one, two, three, or more teeth per stroke of said rocking member depending upon the length of stroke of said rocking member. Thus a means has been provided for controlling the operation and speed of rotation of the winding drum 19 in a simplified manner remote from said winding drum.

It should be noted that as the guide cam 39 is pivotally moved about the axis of the shaft 18 in

such a manner as to permit the pawl 22 to engage the ratchet 20, that tension on the tension spring 42 is increased which in turn increases tension on the flexible cable 35 and maintains the required tension on said cable during the drive 5 operation and permits said cable to effect an improved positive, controlled drive means for the arm 29 and rocking member 23.

A flexible cable 47 is adapted to be secured to and wound on the winding drum 19 and, as is 10 herein preferably shown, extends therefrom along the track 12 to a position remote from the mine cars 11 around a sheave block 48 toward said mine cars and is adapted to have its free end secured thereto. Thus, as one car is being loaded 15 and tension is applied to the flexible member 46, the winding drum 19 may be rotated at the desired speed controlled by the application of tension on said flexible member by the operator for moving each mine car during the loading operation and 20 permitting the trimming of said car to the proper height for the entire length thereof and for moving the next car 11 beneath the discharge end of the pan line 10 after one car has been loaded.

It may thus be seen that a simplified device 25 has been provided which is operated by a shaker conveyor pan line and controlled in a simplified manner for pulling cars along the track beneath the discharge end of said pan line, and permitting said cars to be uniformly loaded without tying 30 up a mine locomotive or necessitating the provision of separate motor driven car pulling means for such operation. It may also be seen that the device of my invention is operated by a shaker conveyor pan line by means of a flexible cable in 35 a simplified manner; that the arrangement of the mechanism for driving the winding drum is such as to permit the device of my invention to be readily adapted to varying mining conditions; that the speed of the winding drum may readily 40 be controlled by the flexible member 46 at a point remote from said winding drum; that tension on the flexible cable 35 for driving the winding drum 19 from the shaker conveyor pan line is increased as the pawl 22 is permitted to engage the ratchet 45 20 for driving said winding drum; and that the device of my invention is of a flexible construction 55 which may be positioned at various locations with respect to the end of the pan line, and which may be readily adapted to various pan lines having 60 different stroke lengths.

While I have herein shown and described one form in which my invention may be embodied, it will be understood that the construction or arrangement of the various parts may be altered 55 or changed without departing from the spirit and scope thereof. Furthermore, I do not wish to be construed as limiting myself to the particular form shown, excepting as it may be limited by the appended claims.

I claim as my invention:

1. A winding device comprising a support, a winding drum carried thereby, and means for operating said winding drum comprising a pawl and ratchet device, a shaker conveyor, and an 65 adjustable connection from said shaker conveyor to said pawl and ratchet device for reciprocating said pawl and ratchet device and rotating said drum.

2. A winding device comprising a support, a 70 winding drum carried thereby, and means for operating said winding drum comprising a pawl and ratchet device, a shaker conveyor, and a flexible connection from said shaker conveyor to said pawl and ratchet device for reciprocating 75

said pawl and ratchet device and rotating said drum.

3. A winding device comprising: a support; a winding drum carried thereby; and means for operating said winding drum comprising: a pawl and ratchet device, a shaker conveyor; a flexible connection from said shaker conveyor to said pawl and ratchet device for reciprocating said pawl and ratchet device and rotating said drum comprising: a flexible member having connection with said shaker conveyor adjacent one of its ends and said pawl and ratchet device adjacent its opposite end; and yieldable means for maintaining tension on said flexible member.

15. 4. In a car puller; a support, a winding drum carried thereby, a flexible member adapted to be wound on said winding drum and have connection with a car remote therefrom, a ratchet on said winding drum; a pawl adapted to engage said ratchet; a rocking member carrying said pawl, a reciprocably movable member, and a flexible member connecting said rocking member with said reciprocably movable member.

25. 5. In a car puller, a support; a winding drum carried thereby, a flexible member adapted to be wound on said winding drum and have connection with a car remote therefrom, a ratchet on said winding drum, a pawl adapted to engage said ratchet, a rocking member carrying said pawl; a reciprocably movable member; a flexible member connecting said rocking member with said reciprocably movable member; and yieldable means for maintaining tension on said flexible member.

30. 6. In an apparatus of the class described; a support including a shaft, a winding drum carried thereby for free rotation with respect thereto, a ratchet on said drum; a rocking member on said shaft; a pawl on said rocking member engaging said ratchet; a yieldable member for holding said rocking member in one position with respect to said shaft and a flexible member connectible with a reciprocably driven member for rocking said rocking member against said yieldable member.

45. 7. In an apparatus of the class described; a support including a shaft; a winding drum carried thereby for free rotation with respect thereto, a ratchet on said drum; a rocking member on said shaft; a pawl on said rocking member engaging said ratchet; a yieldable member for holding said rocking member in one position with respect to said shaft, a guide cam on said shaft having engagement with said pawl for disengaging said pawl from said ratchet or permitting said pawl to selectively engage said ratchet for

50. moving said drum a distance of one or more teeth of said ratchet upon reciprocation of said rocking member; a yieldable connection between said guide cam and said rocking member, a reciprocably driven member, a flexible member connectible with said reciprocably driven member and rocking member for rocking said rocking member upon reciprocation of said reciprocably driven member.

65. 8. In an apparatus of the class described; a support including a shaft, a winding drum carried thereby for free rotation with respect thereto, a ratchet on said drum; a rocking member on said shaft; a pawl on said rocking member engaging said ratchet; a yieldable member for holding said rocking member in one position with respect to said shaft, a guide cam on said shaft having engagement with said pawl for disengaging said pawl from said ratchet or permitting said pawl to selectively engage said ratchet for

moving said drum a distance of one or more teeth of said ratchet upon reciprocation of said rocking member; a yieldable connection between said guide cam and said rocking member, a reciprocably driven member, a flexible member connectible with said reciprocably driven member and rocking member for rocking said rocking member upon reciprocation of said reciprocably driven member; and means for operating said guide cam from a position remote from said winding drum.

9. In combination with a shaker conveyor; a pan line; a support; a winding drum carried thereby; means for operating said winding drum comprising a pawl and ratchet device; controlling means for said pawl and ratchet device operable from a point remote from said winding drum, and a flexible connection from said pawl and ratchet device to said pan line for reciprocating said pawl and ratchet device upon reciprocation of said pan line.

10. In combination with a shaker conveyor; a pan line; a support; a winding drum carried thereby; means for operating said winding drum comprising a pawl and ratchet device; controlling means for said pawl and ratchet device operable from a point remote from said winding drum; a flexible connection from said pawl and ratchet device to said pan line for reciprocating said pawl and ratchet device upon reciprocation of said pan line and yieldable means interposed between said pawl and ratchet device and support for maintaining tension on said flexible member.

11. In combination with a shaker conveyor, a reciprocably movable pan line, and winding means operated thereby comprising a winding drum, means for supporting said winding drum comprising a plurality of jacks adapted to be supported between a mine roof and mine bottom having a support frame carried thereby for vertical adjustable movement with respect thereto, a shaft supported by said support frame having said winding drum mounted thereon; a rocking member on said shaft having a pawl pivotally mounted thereon, a ratchet on said drum adapted to be engaged by said pawl, a guide cam adapted to engage said pawl for holding said pawl in a disengaged position from said ratchet or permitting said pawl to engage said ratchet; a lever

40. arm extending from said rocking member having a flexible member connected thereto adjacent the end thereof; a connection from said flexible member to said pan line and a yieldable connection from said guide cam to said lever arm for holding said flexible member in tension.

12. In combination with a shaker conveyor, a reciprocably movable pan line, and winding means operated thereby comprising a winding drum 60 comprising a plurality of jacks adapted to be supported between a mine roof and mine bottom having a support frame carried thereby for vertical adjustable movement with respect thereto, a shaft supported by said support frame having said winding drum mounted thereon, a rocking member on said shaft having a pawl pivotally mounted thereon, a ratchet on said drum adapted to be engaged by said pawl, a guide cam adapted to engage said pawl for holding said pawl in 65 engagement with said ratchet or disengaging said pawl from said ratchet; a lever arm extending from said rocking member having a flexible member connected thereto adjacent its outer end, a connection from said flexible member to said pan 70 line.

- line, a yieldable connection from said guide cam to said lever arm for holding said flexible member in tension and means operable against said yieldable member for controlling the position of 5 said guide cam with respect to said pawl from a position remote from said winding drum. 5
13. In combination with a shaker conveyor, a shaker conveyor pan line having a discharge end, a track-mounted car adapted to be positioned adjacent the discharge end of said shaker conveyor pan line, and means operated by said shaker conveyor pan line for moving said track-mounted car under the discharge end of said shaker conveyor pan line comprising a winding drum and a 10 connection from said shaker conveyor pan line to said winding drum for transferring the translational movement thereof into rotational movement. 15
14. In combination with a shaker conveyor, a shaker conveyor pan line having a discharge end, a track-mounted car adapted to be positioned adjacent the discharge end of said shaker conveyor pan line, and means operated by said shaker conveyor pan line for moving said track-mounted car under the discharge end of said shaker conveyor 20 pan line comprising a winding drum, and a connection from said shaker conveyor pan line to said winding drum for transferring the translational movement thereof into rotational movement comprising a pawl and ratchet device, and a flexible operative connection from said shaker conveyor pan line to said pawl and ratchet device. 25
15. In combination with a shaker conveyor, a shaker conveyor pan line having a discharge end, a track-mounted car adapted to be positioned adjacent the discharge end of said shaker conveyor pan line, and means operated by said shaker conveyor pan line for moving said track-mounted car under the discharge end of said shaker conveyor pan line comprising a winding drum and a connection from said shaker conveyor pan line to said winding drum for transferring the translational movement thereof into rotational movement comprising a pawl and ratchet device, a flexible operative connection from said shaker conveyor pan line to said pawl and ratchet device and means operable from a point remote from 30 said winding drum for controlling the operation of said pawl and ratchet device and maintaining tension on said flexible member. 35
16. In a winding drum, a support, a shaft carried thereby, a winding drum on said shaft, a ratchet on said winding drum, a rocking member on said shaft, a pawl on said rocking member engageable with said ratchet, means for holding said pawl in disengagement with said ratchet or permitting said pawl to engage said ratchet for moving said winding drum a predetermined distance 40 for each stroke of said rocking member comprising a guide shield adapted to have operative engagement with said pawl, means for rocking said rocking member comprising an arm extending from said rocking member, a reciprocably movable member, and a flexible cable operatively connected between said arm and said reciprocably movable member, and means for operating said guide shield and maintaining tension on said flexible cable comprising an operating member connectible with said guide shield for manually moving said guide shield in one direction and a yieldable member connected between said guide shield and lever arm. 45
17. In a winding drum, a support, a shaft carried thereby, a winding drum on said shaft, a ratchet on said winding drum, a rocking member on said shaft, a pawl on said rocking member engageable with said ratchet, means for holding said pawl in disengagement with said ratchet or permitting said pawl to engage said ratchet for moving said winding drum a predetermined distance 50 for each stroke of said rocking member comprising a guide shield adapted to have operative engagement with said pawl, means for rocking said rocking member comprising an arm extending from said rocking member, a reciprocably movable member, and a flexible cable operatively connected between said arm and said reciprocably movable member, and means for operating said guide shield and maintaining tension on said flexible cable comprising an operating member connectible with said guide shield for manually moving said guide shield in one direction and a yieldable member connected between said guide shield and lever arm. 55
18. In a winding drum, a support, a shaft carried thereby, a winding drum on said shaft, a ratchet on said winding drum, a rocking member on said shaft, a pawl carried by said rocking member for selective engagement with said ratchet, another ratchet on said winding drum, a dog engaging said ratchet to hold said winding drum from rotation in one direction, means for permitting said pawl to selectively engage said ratchet comprising a guide shield adapted to have 60 operative engagement with said pawl, means for rocking said rocking member comprising an arm extending therefrom, a reciprocably movable shaker conveyor pan line, a flexible member operatively connected between said shaker conveyor pan line and the end of said arm, a tension spring connected between said support and rocking member for holding said flexible member in tension, and other means for increasing the tension on said flexible member as said pawl is permitted to disengage said ratchet comprising means for moving said guide cam, and a connection between said guide cam and arm. 65
19. In a winding drum, a support, a shaft carried thereby, a winding drum on said shaft, a ratchet on said winding drum, a rocking member on said shaft, a pawl carried by said rocking member for selective engagement with said ratchet, another ratchet on said winding drum, a dog engaging said ratchet to hold said winding drum from rotation in one direction, means for permitting said pawl to selectively engage said ratchet comprising a guide shield adapted to have operative engagement with said pawl, means for rocking said rocking member comprising an arm extending therefrom, a reciprocably movable shaker conveyor pan line, a flexible member operatively connected between said shaker conveyor pan line and the end of said arm, a tension spring connected between said support and rocking member for holding said flexible member in tension, and other means for increasing the tension on said flexible member as said pawl is permitted to disengage said ratchet comprising means for moving said guide cam, and a tension spring interposed between said guide cam and arm. 70
20. In a winding drum, a support, a shaft carried thereby, a winding drum on said shaft, a ratchet on said winding drum, a rocking member on said shaft, a pawl carried by said rocking member for selective engagement with said ratchet, another ratchet on said winding drum, a dog engaging said ratchet to hold said winding drum from rotation in one direction, means for permitting said pawl to selectively engage said ratchet comprising a guide shield adapted to have operative engagement with said pawl, means for rocking said rocking member comprising an arm extending therefrom, a reciprocably movable shaker conveyor pan line, a flexible member operatively connected between said shaker conveyor pan line and the end of said arm, a tension spring connected between said support and rocking member for holding said flexible member in tension, and other means for increasing the tension on said flexible member as said pawl is permitted to disengage said ratchet comprising means for moving said guide cam, and a tension spring interposed between said guide cam and arm. 75

- ber on said shaft, a pawl carried by said rocking member for selective engagement with said ratchet, another ratchet on said winding drum, a dog engaging said ratchet to hold said winding drum from rotation in one direction, means for permitting said pawl to selectively engage said ratchet comprising a guide shield adapted to have operative engagement with said pawl, means for rocking said rocking member comprising an arm extending therefrom, a reciprocably movable shaker conveyor pan line, a flexible member operatively connected between said shaker conveyor pan line and the end of said arm, a tension spring connected between said support and rocking member for holding said flexible member in tension, means for moving said guide cam in such a direction as to disengage said pawl from said ratchet comprising a tension spring connected between said arm and guide cam, and means for moving said guide cam in such a direction as to permit said pawl to engage said ratchet and simultaneously increase tension on said flexible cable comprising an operating member for moving said guide cam against said tension member.
21. A winding device comprising a support, a winding drum carried thereby, and means for operating said winding drum comprising a pawl and ratchet device, a shaker conveyor, and an operative connection from said shaker conveyor to said pawl and ratchet device for reciprocating said pawl and ratchet device and rotating said drum.
22. In an apparatus of the class described, a support including a shaft, a winding drum carried thereby for free rotation with respect thereto, a ratchet on said drum, a rocking member on said shaft, a pawl on said rocking member engaging said ratchet, a yieldable member for holding said rocking member in one position with respect to said shaft, a guide cam on said shaft having engagement with said pawl for disengaging said pawl from said ratchet or permitting said pawl to selectively engage said ratchet for moving said drum a distance of one or more teeth of said ratchet per stroke of said rocking member, a yieldable connection between said guide cam and said rocking member, a reciprocably driven member, and a member connectible with said reciprocably driven member and rocking member for rocking said rocking member upon reciprocation of said reciprocably driven member.
23. In an apparatus of the class described, a support including a shaft, a winding drum carried thereby for free rotation with respect thereto, a ratchet on said drum, a rocking member on said shaft, a pawl on said rocking member engaging said ratchet, a yieldable member for holding said rocking member in one position with respect to said shaft, a guide cam on said shaft having engagement with said pawl for disengaging said pawl from said ratchet or permitting said pawl to selectively engage said ratchet for moving said drum a distance of one or more teeth of said ratchet per stroke of said rocking member, a reciprocably driven member, and a member connectible with said reciprocably driven member and rocking member for rocking said rocking member upon reciprocation of said reciprocably driven member, a yieldable member for holding said rocking member in one position with respect to said shaft, a guide cam on said shaft having engagement with said pawl for disengaging said pawl from said ratchet or permitting said pawl to selectively engage said ratchet for moving said drum a distance of one or more teeth of said ratchet upon reciprocation of said rocking member, a yieldable connection between said guide cam and said rocking member, a reciprocably driven member, a member connectible with said reciprocably driven member and rocking member for rocking said rocking member upon reciprocation of said reciprocably driven member, and means for operating said guide cam from a position remote from said winding drum.
24. In combination with a shaker conveyor, a pan line, a support, a winding drum carried thereby, means for operating said winding drum comprising a pawl and ratchet device, controlling means for said pawl and ratchet device operable from a point remote from said winding drum, an operative connection from said pawl and ratchet device to said pan line for reciprocating said pawl and ratchet device upon reciprocation of said pan line, and yieldable means interposed between said pawl and ratchet device and support for maintaining tension on said flexible member.
25. In combination with a shaker conveyor, a reciprocably movable pan line, and winding means operated thereby comprising a winding drum, means for supporting said winding drum comprising a plurality of jacks adapted to be supported between a mine roof and mine bottom having a support frame carried thereby for vertical adjustable movement with respect thereto, a shaft supported by said support frame having said winding drum mounted thereon, a rocking member on said shaft having a pawl pivotally mounted thereon, a ratchet on said drum adapted to be engaged by said pawl, a guide cam adapted to engage said pawl for holding said pawl in a disengaged position from said ratchet or permitting said pawl to engage said ratchet, a lever arm extending from said rocking member, a connection from said lever arm to said pan line and a yieldable connection from said guide cam to said lever arm.

WILLIAM E. GOODMAN.
